ROTARY PUMP OR MOTOR

Hugo A. Centervall, Brooklyn, N. Y., assignor to
 Manly Corporation, New York, N. Y., a corpora-
 tion of Delaware

Application June 25, 1936, Serial No. 87,176

21 Claims. (Cl. 103—120)

This invention relates to rotary fluid pumps or motors of the vane type whose capacity or output is variable independently of change of speed of rotation, that is to say, whose volumetric capacity per revolution can be regulated or varied. It relates more particularly to improvements in that portion of the pump by means of which such variation or regulation of capacity is obtained.

Pumps and motors of this general class find their widest use at present as hydraulic devices, that is, devices for handling or whose motive fluid is a liquid, such, for example, as oil, and the pump or motor of the present invention will be described in connection with such use. It will be understood, however, that the invention is applicable to pumps or motors operating with elastic fluids.

My copending application Serial No. 720,418, filed April 13, 1934, relates to such a pump or motor, and while the construction therein disclosed has been found to be successful, the present invention concerns certain improvements, and the general object of the present invention is to simplify the construction, rendering the parts easier to assemble and reducing the cost of manufacture without compromising reliability of operation, and retaining the features of my previous pump of quietness of operation and substantial freedom from vibration even when operating at hydraulic pressures up to 1,000 pounds per square inch, or more, and at all loads from zero to the maximum output for which the pump or motor is designed.

Pumps and motors of the type under consider-
 35 sation comprise a rotor carrying vanes which are movable in and out in a general radial direction, and arranged to rotate within a chamber having side walls which closely fit the sides of the rotor and side edges of the vanes. A
 40 trackway for guiding and controlling the inward and outward movement of the vanes as the rotor revolves comprises one or more pairs of abutments and interconnecting flexible track elements. The work of the pump or motor is done
 45 while the vanes travel across the arcuate length of one of these abutments of each pair, termed the "working" or "pumping arc", which is spaced radially from the surface of the rotor, the working fluid being received on one side of this arc
 50 or abutment and discharged on the other. The other abutment of each pair serves to separate one of these discharge areas from the adjacent inlet area. The regulation of the capacity of the
 55 pump or motor is effected by moving or adjust-
 ing the working or pumping abutment radially

with respect to the circumferential surface of the rotor, the flexible track elements having extensible connections with one abutment thereby permitting such adjustment without changing the radial position of the other abutment of each pair, which is preferably arranged in fixed position adjacent the surface of the rotor. An important object of the invention is to improve the construction and arrangement of this vane track and its associated mechanism by means of which the volumetric capacity per revolution of the rotor of the pump or motor is determined, and regulated or varied, and by which the inward and outward movements of the vanes are controlled.

In the present pump construction the aligning means (that is, the means for maintaining even relationship between the overlapping parts of the track surface at the extensible connections), and the flexing control means (that is, the means for flexing the flexible portions of the track) are arranged on the abutments, whereas in the earlier construction both of these means were on the end plates which form the side walls of the pump chamber.

In the former construction also the connect-
 25 ing or flexible track elements were secured to the movable abutments, whereas in the pres-
 ent construction the flexible track elements are preferably secured to the fixed or stationary abut-
 30 ments, the flexing and aligning means being car-
 ried by the movable abutments. In addition, in
 my present construction, the stationary abut-
 35 ments and flexible track elements comprise a uni-
 tary composite structure which is mounted on a
 continuous ring-like spacer block to securely hold
 the flexible track elements in place with their
 40 surfaces in proper relation to the surface of the
 fixed abutment.

The arrangement of the present invention fur-
 thermore provides certain improvements in the 40
 particular mechanism employed for aligning and
 controlling the flexing of the flexible track ele-
 ments. The present invention still further pro-
 vides for a pump in which the direction of flow
 45 of fluid may be reversed, or a motor whose direc-
 tion of rotation may be reversed, and the pump
 capacity per revolution, or the power output, may
 be continuously varied, that is, varied in infinitely
 50 small amounts in both directions of fluid flow or
 motor rotation, as the case may be.

The invention will be understood from a con-
 sideration of the accompanying drawings which
 illustrate, by way of example, a number of em-
 bodiments of the invention in a pump of variable
 55 capacity.

In these drawings:

Fig. 1 is a view of the pump, the left hand half of which is in transverse section taken along the vertical center line 1—1 of Fig. 2, and the right half of which is in side elevation with the cover and its adjacent end plate removed;

Fig. 2 is a view in central, longitudinal section, taken along the line 2—2 of Fig. 1;

Fig. 3 is a view in side elevation showing the pump casing with its adjacent end plate in position, the rotor and casing cover being removed;

Fig. 4 is a perspective view of a pair of flexible track elements with part of the flexing control mechanism integral therewith;

Fig. 5 is a perspective view of a movable abutment and its associated parts;

Figs. 6 and 6a show the relative positions of the movable abutments and flexible track elements and associated mechanism in their two extreme positions of adjustment;

Fig. 7 is a view transverse the axis of rotation of a modified form of pump with the enclosing casing, driving shaft and end plates removed, the left half being partly in section;

Figs. 8 and 8a are fragmentary views somewhat similar to Fig. 7 showing for this modification the relative positions of the movable abutments and flexible track elements and their associated mechanism in their two extreme positions of adjustment; and

Figs. 9 and 10 are views, partly schematic showing another modified form of pump with the enclosing casing, driving shaft and end plates removed, in which the direction of flow of the fluid may be reversed.

Referring first to the embodiment of the invention illustrated in Figs. 1-6a of these drawings, as shown in Fig. 2 the pump includes a casing 10 and a cover 11 which are provided with suitable cooperating faces and which are held together by screws 12, appropriate packing 13 being used to prevent leakage. The pump is supported by a base 15 formed integrally with the casing 10.

A pair of disc-shaped end plates 20 are positioned within the interior of the casing 10, each of which is formed with a hub 21 which snugly fits into a suitable bore in the casing 10 and cover 11 respectively. The end plates 20 are separated by a pair of spacer blocks or central distance-pieces 23 (Figs. 1 and 2) which form substantially fluid tight fits therewith.

Each spacer block has a nearly semi-circular outer surface adapted to substantially conform with the interior of the casing 10 and an inner surface suitably cut away to provide space for other parts of the pump to be later described. The spacer blocks 23 are diametrically positioned and their parallel opposing ends in this embodiment are horizontal when the parts are in position. Each spacer block is located by a bolt 24 (to be referred to later) whose end extends beyond the exterior of the casing 10 and is threaded to receive a nut 25 (Fig. 2) and each spacer block is also provided with holes through which pass the screws 12 as clearly shown in Fig. 1.

The pump rotor 26 is positioned in the chamber formed between the end plates 20 and the two spacer blocks 23 and is of a width slightly less than that of the spacer blocks 23. Rotor 26 is rotatably supported upon its hubs 27 which extend into the bores of the hubs 21 of the end plates 20. The arrangement is such that the rotor 26 is free to rotate while forming substantially fluid tight running fits with the cooperating

surfaces of the end plates 20. Rotor 26 is also formed with a plurality of substantially radial vane slots 28, each of which is provided with a vane 29 of substantially the same width as the rotor 26 and preferably of a length slightly less than that of the vane slots 28.

The rotor is driven in such a way that slight misalignment of the rotor and drive shaft, or end thrust of the shaft, will not cause the rotor to bind. The driving shaft 31 is rotatably supported by a bearing element 32 carried by the cover 11 and by another bearing element 33 carried in a bore formed in the casing 10 through which the shaft 31 passes, said bore being closed by a cover plate 16. The driving shaft 31 passes loosely and slidably through the bore of the rotor 26 and is suitably keyed thereto, as by a key 34 slidably engaging a keyway in the bore of the rotor 26, in such manner that the driving shaft 31 may move lengthwise with respect to the 20 rotor.

The space within the cavity or chamber formed between the end plates 20 and the spacer blocks 23 and which surrounds the rotor 26 is divided into a plurality of pumping sections, preferably two, each consisting of a working or pumping chamber flanked by inlet and outlet spaces. In this embodiment the space surrounding the rotor 26 is divided by a pair of fixed abutments 36 (Fig. 1) which extend inward from the spacer blocks 23 and are positioned above and below the rotor 26. Each fixed abutment 36 is substantially the same width as the spacer blocks 23 and is provided with an interior arcuate surface adapted to form a substantially fluid tight sliding fit with the ends of vanes 29. According to this embodiment of the invention these abutments are formed on the heads of bolts 24. The inner arcuate surfaces of the fixed abutments 36 form part of the vane track for guiding the vanes and along which the exposed ends of the vanes 29 move in sliding contact as the rotor revolves. These surfaces are preferably concentric with the periphery of the rotor 26 and of an angular length equal to or slightly greater than the angular distance between a pair of adjacent vanes 29.

The working or pumping chambers of the two pumping sections are formed by means of two diametrically positioned members 40, hereafter termed "movable abutments", one of which is shown in perspective in Fig. 5. The pumping chambers are comprised by the spaces between the two adjacent vanes which, at any given instant, are moving in contact with a portion of the inner ends of each of these movable abutments 40. The size of these pumping chambers and hence the volume of fluid delivered by the pump per revolution of the rotor are determined by the distance of the inner ends of abutments 40 from the surface of rotor 26. In order to regulate or vary the output or capacity, that is, the "stroke" of the pump, these members are arranged to be radially adjustable, preferably conjointly.

Since full operating fluid pressure exists on opposite sides (in the direction of the circumference of the rotor) of movable abutments 40, they are formed with rectangular portions 41 having a width equal to the distance between the opposing faces of the end plates 20 and a height equal to the distance between the opposing horizontal ends of the spacer blocks 23. Each abutment 40 is slidably supported thus by its rectangular portion 41 and the arrangement is such that portion 41 forms substantially fluid tight 75

sliding joints with the opposing faces of the end plates 20 and the supporting horizontal ends of the spacer blocks 23. A cylindrical portion 42 extends outward from the rectangular portion 41 of each movable abutment 40 and projects through an opening 18 in the pump casing 10 and through an appropriate aperture in the cover 19 which closes opening 18.

The radial adjustment of the movable abutments 40, in order to regulate or vary the pump output, may be effected by any suitable means, not shown, which may be conveniently connected with the outer ends of the cylindrical portions 42. For connection to such output or "stroke" adjusting mechanism the links 42^a are provided. The maximum inward and outward movement of abutments 40 is limited by suitable stops. In this instance these include the enlarged inner ends of the abutments and washers 43 which are adapted to be held in appropriate grooves in the cylindrical portions 42 as indicated by dotted lines at 44 in Fig. 1. These washers are U-shaped, that is, open at one side to permit assembly.

The portion 45 of the inner end of each movable abutment 40 which constitutes the outer wall of one of the pumping chambers, forms part of the vane track which will be referred to as the "pumping arc". The center line of each pumping arc is preferably in line with the horizontal center line of a rectangular portion 41, and the two pumping chambers or pumping arcs are diametrically opposite one another.

Fluid is admitted to the pumping chambers at one side of the vanes as they approach each pumping chamber, and fluid is discharged from the pumping chambers in like manner as the vanes recede from each pumping chamber. The inlet and outlet ports by which this is accomplished are located in the right hand end plate 20 as viewed in Fig. 2, although the plane on which the section of Fig. 2 is taken does not pass through any of these ports. These ports are shown, however, in Fig. 3 as narrow arcuate slots, and will be described in more detail further on, together with their connections with the main inlet and outlet passages of the pump.

The pumping arcs 45 are preferably of length, in a circumferential direction, equal to or slightly greater than the distance between the ends of a pair of adjacent vanes 29 when in their maximum radially outward position. The arcs 45 may be of any preferred curvature but are preferably made concentric with the rotor 26 when the movable abutments 40 are in the position at which the pump is intended to receive its greatest use. In this embodiment the pumping arcs 45 are concentric with the rotor 26 when the movable abutments 40 are midway between their extreme inward and outward positions of adjustment. By this arrangement the radial movement of the vanes 29 while passing across the pumping arcs 45 and subject to unbalanced working pressure is kept at a minimum and is so small that in practice it is negligible at all outputs.

The vanes 29 are conveyed or guided in their in and out movement to and from the fixed abutments 36 and movable abutments 40, as the rotor revolves, by means of connecting track elements which for convenience are termed "flexible track elements", although it will be understood that parts thereof may be rigid, as shown for example in Figs. 1 and 4. Up to this point the pump of my present invention is not unlike the one disclosed in my earlier application referred to above. Ac-

cording to the embodiment of the invention shown in Figs. 1-6a, one of the ends of each of the flexible track elements is adapted to be fixedly supported upon the fixed abutments 36, and the flexible elements are formed in pairs. As shown in Figs. 1 and 4, each pair of flexible track elements includes a central portion 50 which is preferably rigid and of substantially the same width as the fixed abutment 36 with which it cooperates. The central portion 50 is adapted to fit within an appropriate recess in the spacer block 23 and is provided with a suitable hole, not shown, through which the bolt 24 passes (see Figs. 1 and 2). The arrangement is such that the central portion 50, the corresponding spacer block 23 and fixed abutment 36 are firmly held together so that the contiguous inner surfaces of the flexible track elements are held continuously in smooth alignment with the arcuate inner surfaces of the fixed abutment 36.

The inner ends of the movable abutments 40 have forked arms 46 extending in an approximately circumferential direction from the rectangular portions 41 (Figs. 1 and 5). These arms, as will be seen presently, coact with and control the position and flexing of the connecting or flexible track elements. The inner arcuate edges of arms 46 are provided with arcs 47 adjacent each side of pumping arc 45 which form part of the vane track. The arcs 47, which may have any suitable radius of curvature, smoothly join the pumping arcs 45 and extend a short distance therefrom.

A flexible arm 52 (Figs. 1 and 4) projects from each end of the central portion 50 of the flexible track elements and extends in an approximately circumferential direction toward its corresponding movable abutment 40 with which it is adapted to connect and cooperate in all positions of adjustment of the movable abutment 40. Each arm 52 terminates in a relatively rigid end portion 53 which is adapted to slidably fit within the fork of the adjacent forked arm 46, and the flexible arms 52, which may be of any suitable width, are here shown as of the same width as these rigid end portions 53. The inner surfaces of the rigid end portions 53 are formed with arcs 54 (Figs. 1 and 4) which constitute parts of the vane track and which preferably have the same curvature as that of the arcs 47 on the forked arms 46 with which they are adapted to overlap and connect at all times.

Each vane 29, during each revolution of the rotor 26, passes to and from each of the elements of the vane track and as these vane track elements are eight in number (two movable abutments 40, two fixed abutments 36 and four flexible track elements) each vane therefore passes from one track element to another eight times per revolution of the rotor 26. Transfer of a vane 29 from one vane track element to another therefore occurs in a very short interval and frequently at comparatively high speeds of relative movement between the end of the vane 29 and the vane track surfaces. This frequency and speed of transfer make it necessary to continuously maintain each vane track element in smooth alignment with its adjacent elements at all "strokes" of the pump, as any roughness or unevenness of the surface of the vane track would interfere with proper movement of the vanes, resulting in unsatisfactory operation of the pump. There is no relative movement between the stationary abutments 36 and the adjacent portions of the flexible track elements,

and alignment between their contiguous vane track surfaces at their juncture is readily maintained by the arrangement already described. Radial adjustment of the movable abutments 40 produces relative movement, however, between the inner ends of these abutments and the flexible track elements so it is necessary to provide means, to be described presently, which assure and maintain proper alignment between the contiguous portions of their vane track surfaces.

Each vane 29 is also reciprocated twice for each revolution of the rotor 26 (which in practice will frequently rotate at speeds of 800-1200 R. P. M.) so that the vanes 29 attain relatively high speeds or radial movement and are subject to rapidly recurring reversal in the direction of their radial motion. It is therefore also necessary to regulate and control the rates of inward and outward movement of the vanes 29, that is, their radial acceleration and deceleration, in order to obtain satisfactory operation of the pump and it is very important and practically essential that their radial movement be smooth and without sudden or violent increase or decrease of radial velocity. It is also important and practically essential that the outward radial acceleration of the vanes be such that the force necessary therefor is within the limit of the centrifugal force produced by rotation of the rotor and acting to urge the vanes outward, in order to maintain continuous contact between the ends of the vanes and the vane track surface.

Radial movement of the vanes 29 is controlled by the vane track, and their rates of radial movement are accordingly regulated by controlling the shape of the vane track throughout the range of adjustment of the movable abutments 40. This control is accomplished by proper proportion of the several elements comprising the vane track 40 and by exerting upon the flexible portions of the vane track simultaneously with the adjustment of the movable abutments 40, force or forces which alter their curvature to a predetermined extent and in a predetermined manner, so that their shape is positively controlled throughout the entire range of adjustment of the movable abutments 40. In the embodiment of Figs. 1-6a the mechanism for exerting this force upon the flexible portions of the vane track includes that employed for maintaining alignment between the contiguous portions of the vane track surfaces of the movable abutments 40 and flexible track elements, and this mechanism which is utilized to perform both of these functions will now be described.

The rigid end portions 53 of the flexible track elements are provided with slots 57 (Figs. 1 and 4), for convenience termed the "guide slots", which are preferably concentric with the arcs 54. Keys 48 fit within these guide slots. These keys 48 (Fig. 1) may be of any suitable shape and are shown as cylindrical pins fixedly supported upon the forked arms 46 of the movable abutments 40, as by closely fitted holes 49 (Fig. 5). The guide slots 57 and their keys 48 cooperate to radially position the rigid end portions 53 with respect to the forked arms 46, and the arrangement is such that the corresponding surface of each arc 56 is maintained even with the surface of its respective adjacent arc 47 on the edges of the forked arms.

While the rigid end portions 53 and the arms 46 are thus radially positioned with respect to each other, the guide slots 57 and their keys 48 if employed alone are not capable of maintaining

the necessary alignment between the arcs 47 and 54 nor of exerting the desired bending force upon the flexible arms 52, as the rigid end portions 53 would then be free to swing around the keys 48 so that there would be no assured alignment and no positive control of the curvature of the flexible arms 52.

The rigid end portions 53 of the flexible track elements are accordingly provided with control members 55 having one of their ends formed integrally with or securely attached to the rigid end portions. The control members 55 are formed with slots 58 (Figs. 1 and 4) for convenience termed the "control slots", which may be given any suitable shape, depending upon the curvature which it is desired to obtain in the flexible arms 52. As here shown the control slots 58 have the same curvature as the arcs 54 and are concentric therewith, and these control slots 58 are also provided with keys 59 which are carried by the forked arms 46 of movable abutments 40. These control slots 58 and their keys 59 cooperate with the guide slots 57 and their keys 48 to maintain the arcs 54 concentric with the arcs 47 and to keep the over-lapping portions of these arcs 25 coincident, while at the same time exerting bending force upon the flexible arms 52 as will be more fully explained presently.

Substantially all radial movement of the vanes 29 occurs while they are moving along that portion of the vane track constituted by the flexible arms 52, so that the rates of their radial movement is controlled by the shape of these flexible arms. The inner surfaces of the flexible arms 52 may be given any suitable curvature or shape but are preferably so formed that they smoothly join with the arcs 54 and with the arcs on the vane track surfaces of the fixed abutments 36. The inner surfaces of the flexible arms 52 are also preferably ground to have the configuration producing the desired rates of radial acceleration and deceleration of the vanes 29 when no flexing or re-forming force is exerted upon said flexible arms 52 by the mechanism provided for this purpose. In this embodiment the arrangement is such that the flexible arms 52 are free from this force when the movable abutments 40 are midway between their extreme inward and outward positions of adjustment, as shown in Fig. 1, and the inner surfaces of said arms 52 are ground to closely approximate segments of a parabola when the movable abutments 40 are in this mid-position which corresponds to approximately "half stroke" of the pump. The flexible arms 52 may also be of any suitable thickness and in the embodiment of Figs. 1-6a are of variable thickness, being thinnest at their central portions and increasing in thickness towards their ends.

Adjustment of the movable abutments 40 radially outward from their mid-position shown in Fig. 1 increases the length of the stroke of the vanes 29 and the output or capacity of the pump and produces relative movement between the forked arms 46 and the rigid end portions 53 of the flexible or connecting track elements. The keys 48 and 59 at the same time move outward in a straight path and tend to impart like motion to the rigid end portions 53 and control members 55 but the guide slots 57 and control slots 58 are so fitted with respect to their keys 48 and 59 that said keys are freely movable lengthwise of said slots while all other relative movement is prevented.

Relative movement in an approximately circumferential direction is thus produced between 75

the arms 46, which carry the keys 48 and 59, and the rigid end portions 53, and hence between the arcs 47 and 54, increasing the circumferential length of the vane track and shortening the overlap between portions of the arcs 47 and 54. All relative movement between these parts is confined to a path determined by the shape of the guide slots 57 and control slots 58 and as these are preferably concentric with the arcs 54, which 5 preferably have the same curvature as the arcs 47, the surfaces of the arcs 47 and 54 are at all 10 times maintained concentric and their overlapping portions coincident.

The constraining action which produces this 15 controlled relative circumferential movement also exerts bending force upon the flexible arms 52. If the guide slots 57 and their keys 48 were alone employed the rigid end portions 53 and their attached control members 55 would tend to rock 20 to a certain extent, around the keys 48 as centers, toward the rotor 26 which would tend to straighten the flexible arms 52 and decrease their curvature. The control slots 58 and their keys 59 positively control this rocking and the shape 25 of said slots determines the amount of rocking which occurs. In this instance the shape of the control slots 58 is such that, as the movable abutments 40 are moved radially outward from their midposition, the control members 55 are rocked 30 toward the rotor to a greater extent than would result if the guide slots 57 and their keys 48 were alone provided and the control members 55 otherwise unconstrained.

This increased rocking of the control members 35 55 and rigid end portions 53 exerts increased positive bending force upon the flexible arms 52 which tends to straighten them and decreases their curvature, with the result that the parabolic portions of the vane track are flattened as the movable abutments 40 are moved outward from their 40 mid-position. This is best shown in Fig. 6a which shows the relative positions of the vane track elements when a movable abutment 40 has been radially adjusted to its extreme outward 45 position, the dotted circular line indicating the periphery of the rotor 26.

The action of the parts just explained is reversed when the movable abutments 40 are adjusted radially inward from their mid-position 50 shown in Fig. 1. The stroke of the vanes 29 and the capacity or output of the pump are then reduced. Relative circumferential movement between the forked arms 46 and rigid end portions 53 takes place in the opposite direction, the circumferential length of the vane track is shortened 55 and the overlap between portions of the arcs 47 and 54 is increased, the surfaces of said arcs 54 being maintained concentric with the surfaces of the arcs 47 and their overlapping 60 portions coincident.

The control slots 58 and their keys 59 again function to positively control the rocking of the control members 55 and rigid end portions 53 around the keys 48 as centers and the shape of 65 the control slots 58 determines the amount of rocking which occurs. In this instance the control members 55 and rigid end portions 53 tend to rock outward or away from the rotor 26, which tends to increase the curvature of the flexible 70 arms 52, but the shape of the control slots 58 is such that the control members 55 are rocked to a greater extent than would occur if guide slots 57 and their keys 48 alone were provided and the control members 55 otherwise unconstrained.

Increased positive bending force is thereby exerted upon the flexible arms 52.

This increased bending force still further increases the curvature of the flexible arms 52 and the arrangement is such that they progressively 5 approach and assume the approximate curvature of arcs concentric with the rotor 26 as the movable abutments 40 continue to be moved radially inward from their midposition. This is best seen in Fig. 6, which shows the relative positions 10 of these parts when a movable abutment 40 is in its extreme inward position of adjustment.

The guide slots 57 and control slots 58 and their keys 48 and 59 perform still another function and serve as dampers for any vibrations that 15 may be set up in the flexible arms 52.

Whenever the movable abutments 40 are moved toward their mid-position shown in Fig. 1, the flexible arms 52 progressively return toward their normal curvature which is resumed when 20 the movable abutments 40 reach this mid-position. Through the entire range of adjustment, therefore, the curvature of the flexible arms 52 is increased and the circumferential length of the vane track simultaneously shortened whenever the movable abutments 40 are moved radially inward; and the curvature of the flexible arms 52 is decreased and the circumferential length of the vane track is simultaneously increased whenever the movable abutments 40 are adjusted 30 radially outward. The curvature of the flexible arms 52 is thus definitely controlled throughout the entire range of adjustment of the movable abutments 40.

The flexible arms 52 may be made to assume 35 almost any desired curvatures as the movable abutments 40 are adjusted radially, so that radial movement of the vanes 29 may be made to occur at practically any predetermined rate. The construction herein described, however, produces 40 radial movement of the vanes 29 at rates which in practice have been found to be entirely satisfactory. The radial acceleration and deceleration of the vanes, as they move across the approximately parabolic curves of the flexible arms 45 52, are free from sudden or violent change and in fact are substantially constant and the outward acceleration is well below that which can be produced by the centrifugal force which acts upon the vanes so that their ends are continuously 50 maintained in contact with the vane track 55 surface.

In practice it has been found that satisfactory 60 operation of the pump and movement of the vanes is obtained with a vane track closely approximating that herein described and which consists of arcs having only four different radii of curvature. These arcs are as follows, reference being made to Figs. 1 and 4-6a, by way of 65 illustration:

(1) The pumping arcs 45 on movable abutments 40.

(2) The arcs on the vane track surfaces of the fixed abutments 36.

(3) Arcs (47, 54) extending circumferentially 65 from each end of each of the pumping arcs 45 and having a common tangent therewith at their juncture. These arcs extend on to the flexible arms 52.

(4) Arcs (not designated by a reference number) extending circumferentially from the ends of each of the arcs on the vane track surfaces of the fixed abutments 36, having common tangents therewith at their juncture, and extending along the flexible arms 52, connecting 70 75

with and also having common tangents with the arcs (47, 54) at their juncture. It will be observed that all of these arcs have common tangents with their contiguous arcs at their juncture. According to this arrangement, a pair of arcs, comprising one each of the arcs (47, 54) and of the arcs extending along the flexible arms 52, connect the pumping arcs 45 with the arcs on the vane track surface of the fixed abutments 36, so that the inner surfaces of track elements 52, 55 and 46 may be formed by arcs of only these two curvatures. This arrangement is convenient in grinding the surfaces of the vane track and assures tangential relationship of each section or arc of the vane track with its contiguous sections or arcs in all positions of adjustment of the movable abutments 40.

In a pump embodying the type of construction described herein there is substantially no change in the curvature of the portions of the vane track immediately adjacent both the fixed abutments 36 and movable abutments 40 when the movable abutments 40 are moved throughout their entire range of adjustment. It is therefore practicable to arrange the sliding connections of the flexible track elements adjacent either the fixed abutments 36 or movable abutments 40, the opposite ends of the flexible track elements for convenience usually being attached to or supported upon the abutments adjacent to them.

Numerous other changes may also be made without departing from the scope of the invention which is not limited to the particular construction illustrated and described. For example, the arcs 47 may have the same curvature as the pumping arcs 45, or the guide slots 57 and control slots 58 may be given a curvature different from that of the arcs 54 and may even be straight (which may be desirable in manufacture) as any errors theoretically resulting therefrom will be very slight and in practice may frequently be neglected. Also each pair of guide and control slots 57 and 58 may be combined to form a single slot of increased length, or they may be positioned upon the forked arms 46 of the movable abutments 40 instead of upon the rigid end portions 53 and control members 55, the keys 48 and 59 then being carried by the rigid end portions 53 and control members 55.

The construction and arrangement of the vane track elements and associated mechanism are important features of this invention and have numerous other advantages. For example, throughout the entire range of adjustment of pumping capacity they provide smooth alignment of the vane track elements and tangential relationship of the flexible arms with those adjoining sections of the vane track which have fixed curvatures. They make the parts substantially self-aligning as the guiding and controlling mechanisms are carried by the parts themselves; this simplifies manufacture and reduces the possibility of improper fit as it is only necessary to accurately position the keys 59 with respect to their corresponding arcs 47 and to accurately position the slots 57 and 58 with respect to the arcs 54. A different material may be used, if desired, for each of the different elements of the vane track (that is, the fixed abutments, movable abutments and flexible track elements) or they may be treated to provide different properties in each. The parts are all relatively simple and inexpensive to manufacture and may readily be made interchangeable.

The vane track elements are also easy to as-

semble. The flexible track elements and fixed abutments 36 are assembled with their spacer blocks 23 and fastened in place by the nuts 25. The movable abutments 40 are then inserted and are radially adjusted and properly aligned with respect to the flexible track elements, the keys 48 and 59 then being inserted in the holes 49 and through the guide slots 57 and control slots 58 respectively. The keys require no fastening as they are held in place by the end plates 20.

The fluid circuit of the pump includes a fluid inlet or suction channel 60 and a fluid outlet or discharge channel 61 (Figs. 2 and 3) connecting respectively with inlet and outlet openings 62 and 63. Suction channel 60 is appropriately connected with its pair of arcuate inlet ports 64 formed in the adjacent end plate 20 shown at the right in Fig. 2. Discharge channel 61 is connected with discharge ports 65. This end plate 20 is also provided with two pairs of vane slot ports 66 and 67, respectively positioned to register with the inner ends of the vane slots 28 and connected by passages 68 and 69 with the ports 64 and 65 respectively. The arrangement is such that the inner ends of the vane slots 28 are connected with fluid under the same pressure as the fluid acting upon the outer ends of their corresponding vanes 29 while said vanes are passing from one abutment to another and hence the vanes 29 are substantially in hydraulic balance when they are moving radially and while passing along the flexible arms 52. The vane slot ports 67 are preferably made of such length that they also connect with the inner ends of those vane slots 28 whose vanes 29 are in contact with the vane track surfaces of the fixed abutments 36 and the pumping arcs 45, so that fluid from the outlet ports 65 is supplied to the inner ends of such vanes to assist in holding their ends firmly in contact with the vane track surfaces as they move across the fixed and movable abutments.

It will be understood that the arrangement of inlet and outlet ports and spaces and of the pumping arcs 45 and fixed abutments 36 produces hydraulic balance of the rotor in a radial direction. The rotor and vanes may also be balanced hydraulically in an axial direction by providing suitable balance ports in the left hand end plate 20 which is adjacent the cover 11, each of these balance ports being adapted to contain fluid under the same pressure as that in its axially opposite port or vane slot port in the other end plate 20.

When the rotor 26 revolves in a clockwise direction as viewed in Fig. 1, fluid enters through the inlet ports 64 and passes into the inlet space of each of the two pumping sections of the pump, that is, into the space between the peripheral surface of the rotor and the surface of the vane track on the following or rear side of each movable abutment 40. Pumping is accomplished by the vanes 29 as they move across the pumping arcs 45 and thus force fluid into the outlet spaces of each of the two working sections of the pump, from which it passes out through the outlet ports 65 and into the outlet channel 61. The outlet spaces correspond with the inlet spaces but are on the leading or front sides of the movable abutments. As already stated, the size of the pumping chambers and the volume of fluid delivered by the pump are determined by the distance of the pumping arcs 45 from the rotor 26; as this distance may be continuously varied in infinitely small increments from minimum to

maximum, the size of the pumping chambers and the volume of fluid delivered by the pump may be likewise varied from minimum to maximum.

In the modified form of the invention shown in Fig. 7 a continuous unitary spacer block 123 of somewhat ring-like shape surrounds the rotor and vane assembly and cooperates with the end plates 20 to form a compartment or chamber substantially fluid tight except for the ports in one of the end plates. The unitary spacer block 123 is radially positioned by its outer circular surface which closely fits within the interior of the casing 10 and may be located circumferentially as by a dowel pin, not shown. It is held against rotation by the bolts 12 which pass through the holes 112.

The unitary spacer block 123 forms the support for all of the vane track elements. The fixed abutments 136 are wedge-shaped and accordingly are supported by their outer portions which are received within appropriately shaped recesses formed in the spacer block 123. The movable abutments 140 are slidably supported upon the spacer block 123 by parallel slideways formed therein, in substantially the same manner as in the embodiment first described, and their cylindrical portions 142 extend outward from the rectangular portions 141 and project through suitable holes in the spacer block 123. In this instance the flexible track elements which connect the fixed abutments 136 and movable abutments 140 are formed integrally with the fixed abutments 136 or securely attached thereto.

All of the vane track elements and associated mechanism are thus carried by and positioned upon the same single member; proper alignment and fit of these parts are thus readily obtained and the possibility of errors is reduced. These elements, when in position upon the unitary spacer block 123, cooperate to form a complete vane track which in effect is a unit independent of any other part of the pump except the adjusting mechanism, so that proper function and positioning of one element with respect to the others is assured. The end plates 20 are also axially positioned with respect to each other by the unitary spacer block 123 and, as the end plates support and position the rotor, the unitary spacer block 123 therefore forms a common reference or positioning member for substantially all of the working parts of the pump.

The vane track elements are all generally similar to those of the embodiment first described. The guide slots 148 are, however, shown as formed in the forked arms 146 of the movable abutments 140 and are preferably concentric with the arcs 147 thereon (which correspond to the arcs 47 of the embodiment first described) although they may have a different curvature or may even be straight as in the first described embodiment. The rigid end portions 153 of the flexible track elements are provided with suitable retaining means, shown as bushings 157 (which may be welded in place if desired), for appropriate keys or pins 159 whose ends are slidably fitted in the guide slots 148. The arrangement and proportions are such that the keys 159 may move lengthwise of the guide slots 148 but prevent any other relative movement between the rigid end portions 153 and arms 146. The rigid end portions 153 are thus radially positioned with respect to the arms 146 and corresponding portions of the arcs 154 on the inner surfaces of said

rigid end portions are maintained substantially even with the surfaces of the arcs 147.

The rigid control members 155 are shown as continuations of the rigid end portions 153 and their ends 156 are adapted to slidably fit in appropriate control slots 158 here shown as formed in the unitary spacer block 123. The arrangement is such that the control members 155 may also pivot a slight amount around their ends 156 as centers, as may be required at various positions of adjustment of the movable abutments 140.

The vane track elements of this modified form cooperate and function in much the same way as those of the embodiment first described. Radial adjustment of the movable abutments 140 produces relative circumferential movement between the forked arms 146 and the rigid end portions 153 of the flexible track elements and thus alters the circumferential length of the vane track. This movement of the rigid end portions 153 causes the control members 155 to tend to rock around the keys 159 as centers, and the amount of this rocking is controlled by the control slots 158 which are shaped and positioned to produce rocking of the control members 155 to the extent necessary to maintain the arcs 154 concentric with the arcs 147 in all positions of the movable abutments 140.

As in the embodiment first described, this controlled rocking of the control members 155 also exerts positive increased bending force upon the flexible arms 152 to positively control their curvature throughout the range of radial adjustment of the movable abutments 140. The arrangement, preferably, is such that no bending force is exerted upon the flexible arms 152 when the movable abutments 140 are in their mid-position shown in Fig. 7. When the movable abutments 140 are adjusted radially outward from this mid-position, the control members 155 exert increased positive bending force upon the arms 152 which decreases their curvature and when they are adjusted radially inward from this mid-position the control members 155 exert increased positive bending force upon the flexible arms 152 which increases their curvature. Figs. 8 and 8a show the relative positions of these parts when a movable abutment 140 is radially adjusted to its extreme inward and extreme outward positions respectively, the dotted circle indicating the periphery of the rotor.

The flexible arms 152 progressively approach their normal curvature whenever the movable abutments 140 are moved toward their mid-position so that throughout the entire range of adjustment the curvature of the flexible arms 152 is decreased whenever the movable abutments 140 are moved outward and the circumferential length of the vane track thus increased, and the curvature of the flexible arms 152 is increased whenever the movable abutments 140 are adjusted radially inward and the circumferential length of the vane track thus shortened.

Among the advantages of this modified form is that the movable abutments 140 are still further simplified and the size of their inner ends is materially reduced. The flexible track elements and control members 155 may be conveniently made from relatively thin strips of material bent to approximate shape and suitably fastened to the wedge-shaped fixed abutments 136 and to the bushings 157, so that it will be necessary to remove only a comparatively small amount of material in making these parts. As

in the embodiment first described, the vane track elements are substantially self-aligning.

Figs. 9 and 10 show the rotor and vane assembly, spacer block and vane track elements of a further modification of the invention in which the direction of flow of the fluid may be reversed and the capacity of the pump continuously varied in infinitely small amounts in both directions of fluid flow.

10 The vane track elements of this modification are substantially identical with those of the embodiments shown in Figs. 1-6a from which they differ principally in that all four abutments are radially adjustable. A pair of adjustable abutments 236 are accordingly substituted for the fixed abutments 36 of the first described embodiment and are slidably supported upon a unitary spacer block 223. The flexible track elements are shown as made integrally with the abutments 236 or as having one of their ends suitably attached thereto, their opposite having sliding connections with abutments 240.

15 The inner end of each of the abutments 236 and 240 is formed with an arc 245, similar to the pumping arcs 45 of the embodiment first described, which is smoothly joined by the contiguous portions of the vane track surface. The outer ends of the cylindrical portions 242 of these abutments may be conveniently connected 20 with appropriate adjusting mechanism, not shown, by which they may be radially adjusted, and the arrangement is preferably such that the two abutments 236 are conjointly adjusted and that the two abutments 240 are likewise 25 conjointly adjusted.

20 The pump functions in the same manner as the embodiment first described when the radial distance from the rotor to the track surfaces of the abutments 236 is less than the radial distance from the rotor to the track surfaces of the abutments 240. The abutments 236 then perform substantially the same functions as the fixed abutments of the first and second described embodiments and divide the space surrounding the rotor into two pumping sections, each comprising a working or pumping chamber flanked by inlet and outlet spaces. The abutments 240 function in the same manner as the movable abutments 40 of the embodiment first described and the arcs 245 on the inner ends thereof are then the pumping arcs. With the rotor revolving in a clockwise direction as viewed in Fig. 9, the spaces 260 will then be the inlet or suction spaces and the spaces 261 will be the outlet or high pressure spaces. The volume of fluid delivered by the pump in this direction of fluid flow may be continuously varied from zero, when the abutments 236 and 240 are equidistant from the rotor, to maximum, when the abutments 236 are in their extreme inward and the abutments 240 in their extreme outward positions of adjustment respectively, as shown in Fig. 9.

25 The functions of the abutments and the direction of fluid flow are reversed when the abutments are adjusted so that the radial distance from the rotor to the track surfaces of the abutments 240 is less than the radial distance from the rotor to the track surfaces of the abutments 236. The abutments 240 then perform the 30 functions of the fixed abutments, dividing the space surrounding the rotor into two pumping sections, and the abutments 236 function as the movable abutments, the arcs 245 on the inner ends thereof then being the pumping arcs. With 35 the rotor continuing in the clockwise direction,

as viewed in Fig. 10, the spaces 261 will then be the inlet or suction spaces and the spaces 260 will then be the outlet or high pressure spaces. The volume of fluid delivered in this direction of fluid flow may likewise be continuously varied from zero to maximum, the maximum volume being delivered when the abutments 236 are in their extreme outward and the abutments 240 in their extreme inward positions of adjustment respectively, as shown in Fig. 10.

10 The volume of fluid delivered by the pump in both directions of fluid flow may, therefore, be continuously varied throughout the entire range from zero to a maximum which is equal to the maximum volume that would be delivered by a comparable non-reversible pump. The abutments 236 and 240 may be adjusted with respect to each other in numerous relative arrangements as no fluid will be delivered by the pump when all abutments are equi-distant from the rotor, 20 while fluid will be pumped in one direction or the other whenever there is any difference in the radial distances from the rotor to the track surfaces of the abutments 236 and 240 respectively.

15 Instead of simultaneously adjusting both pairs of abutments 236 and 240, variation of capacity may be obtained by adjusting either pair, leaving the other pair in close proximity to the surface of the rotor, as in the case of the fixed abutments of the embodiments of the invention shown in 25 Figs. 1-6a and 7-8a. With this method of operation, at zero stroke, that is, when the output of the pump is zero, all four abutments are equi-distant from but close to the surface of the rotor. When it is desired to cause the pump to deliver 30 fluid, that pair of abutments is adjusted outwardly from the rotor which will produce the desired direction of fluid flow, and the extent of such outward movement determines the fluid output 35 of the pump.

20 Alignment of the contiguous vane track surfaces of the abutments 240 and of the flexible track elements is at all times maintained and curvature of the flexible arms 252 is decreased whenever the circumferential length of the vane 45 track is increased and their curvature is increased whenever the circumferential length of the vane track is shortened.

25 Reversal of direction of fluid flow may also be obtained when fixed abutments are employed, as 50 in the first and second described embodiments, by increasing the radial distance between the rotor from the track surfaces of the fixed abutments and by providing movable abutments capable of being so adjusted radially that their track surfaces may be positioned a distance from the rotor which is less than, equal to or greater than the radial distance separating the rotor and the track surfaces of the fixed abutments. With this arrangement, however, the maximum volume of 55 fluid which can be delivered in each direction of fluid flow is materially reduced in comparison with the maximum volume which could be delivered by a comparable non-reversible pump, as the latter equals the total of the maximum volumes 60 which can be delivered in both directions of fluid flow by a reversible pump of this character.

30 When the direction of fluid flow is reversed the spaces 260 and 261 exchange functions, becoming alternately inlet and outlet spaces. It is therefore desirable to modify simultaneously the arrangement of the vane slot ports so as at all times to supply to the inner ends of the vane slots of those vanes which are in contact with the abutments 236 and 240, fluid under the same 75

pressure as that in whichever of the spaces 260 or 261 are at the time serving as the outlet or high pressure spaces, in order to assist in keeping the ends of said vanes firmly in contact with the 5 vane track surfaces of these abutments. An arrangement by which this may be accomplished is shown, partly schematically, in Figs. 9 and 10.

The end plates 20 are accordingly modified to provide four vane slot ports 264, indicated by 10 dotted lines in Figs. 9 and 10, separate from the vane slot ports 266 and 267, the latter being of equal length and positioned to connect with the inner ends of the vane slots as the vanes therein pass through the spaces 260 and 261 respectively. 15 The vane slot ports 264 are positioned radially in line with the arcs 245 on the inner ends of the abutments 236 and 245 and have an angular length substantially equal to or slightly greater than the angular length of the arcs 245. The 20 vane slot ports 264 are adapted to be connected with whichever of the spaces 260 or 261 are at the time the outlet or high pressure spaces and hence are connected through suitable passages with a circular duct 263 which in turn is connected 25 through pipe 265 with a valve chamber 272 by which connection is made to one or the other of spaces 260 and 261 through pipes 268 and 269. Communication between the duct 263 and spaces 260 and 261 is controlled by a pair 30 of check valves 270 and 271, one of which opens to admit fluid to pipe 263 whenever the pressure therein is less than the pressure in pipes 268 or 269, but which closes when pressure in the pipe 35 265 exceeds the pressure in those pipes. Figs. 9 and 10 show the valve chamber 272 connected with the spaces 261 and 260, respectively, each of which is an outlet or high pressure space when the vane track elements are in the positions of 40 adjustment shown in the respective figures. By this arrangement the chamber 272 and the vane slot ports 264 are at all times supplied with fluid from whichever of the spaces 260 or 261 is at the time the high pressure or outlet space.

The reversible pump herein disclosed possesses 45 substantially all the advantages of the non-reversible type in addition to its ability to reverse the direction of fluid flow and to deliver full volume in both directions of flow. This reversing feature has numerous well known advantages and makes the pump suitable for use in a larger number of applications and for a larger number of 50 purposes.

While the device has been described as a pump, it will also operate as a fluid motor when supplied with fluid under suitable pressure. The 55 cycle of operation will, of course, be reversed. When employed as a motor, it may be desired to introduce mechanical or hydraulic pressure means tending to force the vanes outward to 60 maintain them at all times in contact with the vane track, particularly if the motor is to be operated at low rotative speeds.

It will be understood that, if desired, my invention can be applied to a single-acting pump, thus, 65 for example, a single pumping space may be employed, a single fixed abutment and a single movable abutment, provided the pump is of the non-reversible type; also that such a single-acting pump can be made reversible by employing two 70 adjustable abutments.

It is to be understood that the several embodiments of my invention have been described for the purpose of illustrating the principle of operation and construction of the apparatus of my 75 present invention, and that changes, some of

which have been indicated in the foregoing description, may be made without departing from the spirit and scope of the invention, which is defined in the appended claims.

What I claim as new and desire to secure by 5 Letters Patent of the United States is:

1. In a rotary pump or motor of variable capacity, a casing, a rotor, a plurality of vanes movable inwardly and outwardly of said rotor, a stationary abutment carried by said casing and 10 having a track surface of fixed curvature, means for varying the capacity of said pump or motor including a track for said vanes comprising an abutment having a track surface of fixed curvature, said last-mentioned abutment being movable 15 to alter the capacity of said pump or motor and to vary the circumferential length of said track, and a flexible element carried at one end by said stationary abutment and having its opposite end engaging a portion of said movable abutment in all positions of said movable abutment. 20

2. In a rotary pump or motor of variable capacity, a rotary assembly including a rotor and a plurality of vanes movable inwardly and outwardly thereof, a casing therefor including a first abutment coacting with a portion of the peripheral surface of the rotary assembly, a second abutment coacting with the vanes of another portion of said rotary assembly and adjustable radially with respect thereto to vary the capacity of the pump or motor, a flexible projection secured to one of said abutments and extending in a circumferential direction to the other of said abutments and forming a track 35 element connecting said abutments to guide said vanes radially as they pass therebetween, and means carried by said other abutment for maintaining the track surface of the end of said flexible projection even with the corresponding 40 surface of said abutment as the adjustable abutment is adjusted radially to vary the capacity of the pump or motor. 45

3. In a rotary pump or motor of variable capacity, a rotor, a plurality of vanes movable inwardly and outwardly of said rotor, a casing therefor including a fixed abutment coacting with the ends of the vanes of a portion of the peripheral surface of the rotor, a movable abutment coacting with the ends of the vanes of another portion of said surface and adjustable 50 radially with respect to said surface to vary the capacity of the pump or motor, a projection secured to said fixed abutment and extending in a circumferential direction therefrom to said movable abutment and forming a track element connecting said abutments to guide said vanes radially as they pass therebetween, said projection having a flexible portion, and means for controlling the flexing of said flexible portion 55 conformably to the adjustment of said movable abutment to vary the capacity of the pump or motor, whereby in all positions of said movable abutment the vanes pass smoothly between said abutments. 60

4. In a rotary pump or motor of variable capacity, a casing, a rotor, a plurality of vanes movable inwardly and outwardly of said rotor, an abutment carried by said casing and having a track surface of fixed curvature, means for 70 varying the capacity of said pump or motor including a track for said vanes comprising a second abutment having a track surface of fixed curvature, said second abutment being movable to alter the capacity of said pump or motor and 75

to vary the circumferential length of said track, and a flexible member secured at one end to said first abutment and having an extensible connection with said movable abutment, and means for controlling the flexing of said flexible member conformably to all positions of said movable element, whereby in all positions thereof the vanes pass smoothly around said track.

5. In a rotary pump or motor of variable capacity, a casing, a rotor, a plurality of vanes movable inwardly and outwardly of said rotor, a stationary abutment carried by said casing and having a track surface of fixed curvature, means for varying the capacity of said pump or motor including a track for said vanes comprising a second abutment having a track surface of fixed curvature, said second abutment being movable to alter the capacity of said pump or motor and to vary the circumferential length of said track, 10 a flexible element carried at one end by said stationary abutment and having its opposite end engaging a portion of said movable abutment in all positions of said movable abutment, and means for exerting bending force upon said flexible element to alter its configuration conformably to the position of said movable abutment to cause said vanes to pass smoothly around said track without abrupt changes in radial velocity.

6. In a rotary pump or motor of variable capacity, a rotor, a plurality of vanes movable inwardly and outwardly of said rotor, a track having a surface adapted to coact with the exposed ends of said vanes to control the reciprocation thereof, said track including an abutment which is adjustable radially to vary the capacity of the pump or motor and a stationary abutment having a flexible projection secured thereto and extending to and connected with said adjustable abutment, said flexible projection having a predetermined curvature and being free from force tending to change its curvature when said adjustable abutment is in one position of adjustment, means carried by said adjustable abutment for exerting bending force upon said flexible projection in a direction tending to increase its curvature when said adjustable abutment is moved in one direction away from said force-free position, and means carried by said adjustable abutment for exerting bending force upon said flexible projection in a direction tending to decrease the curvature of said abutment when said adjustable abutment is moved in the opposite direction away from said force-free position.

7. In a rotary pump or motor of variable capacity, a rotor, a plurality of vanes movable inwardly and outwardly of said rotor, a casing therefor including a first abutment coacting with the ends of the vanes of a portion of the peripheral surface of the rotor, a second abutment coacting with the ends of the vanes of another portion of said surface, one of said abutments being adjustable radially with respect to the surface of the rotor to vary the capacity of the pump or motor, a member extending in a circumferential direction and forming a vane track element connecting said abutments to guide the vanes radially as they pass therebetween, said member being secured at one end to one of said abutments, and at its opposite end having an extensible connection with the other of said abutments, said member having a flexible portion, and means in part supported on the abutment having said extensible connection for controlling the flexing of said member conformably to

the adjusted position of said adjustable abutment.

8. In a rotary pump or motor of variable capacity, a rotor, a plurality of vanes movable inwardly and outwardly of said rotor, a casing therefor including a first abutment coacting with the ends of the vanes of a portion of the peripheral surface of the rotor, a second abutment coacting with the ends of the vanes of another portion of said surface, a projection on one of said abutments and extending in a circumferential direction to the other abutment and forming a track element connecting said abutments to guide said vanes radially as they pass therebetween, said projection having a flexible portion, means for radially adjusting one of said abutments with respect to the surface of the rotor to vary the capacity of the pump or motor, and means carried by the end of said projection and by the other of said abutments for maintaining the track surface of the end of said projection substantially even with the corresponding surface of said other abutment and for controlling the flexing of said projection when the adjustable abutment is moved to change the capacity of the pump or motor, thereby providing the right curvature to produce a smooth guiding of the vanes at all capacities.

9. In a rotary pump or motor of variable capacity, a rotor, a plurality of vanes movable inwardly and outwardly of said rotor, a casing therefor including side walls coacting with the sides of the rotor, a first abutment coacting with the ends of the vanes of a portion of the peripheral surface of the rotor, a second abutment coacting with the ends of the vanes of another portion of said surface, one of said abutments being adjustable radially with respect to the surface of the rotor to vary the capacity of the pump or motor, a member extending in a circumferential direction and forming a vane track element connecting said abutments to guide the vanes radially as they pass therebetween, said member being secured at one end to one of said abutments, and having at its opposite end a rigid portion having a track surface, said member having a flexible portion, and means carried by the other of said abutments for coacting with said rigid portion to alter and control the configuration of said flexible portion when the adjustable abutment is moved to change the capacity of the pump or motor, thereby providing the right curvature in said member to produce a smooth guiding of the vanes at all capacities.

10. In a rotary pump or motor of variable capacity, a rotor, a plurality of vanes movable inwardly and outwardly of said rotor, a casing therefor including side walls coacting with the sides of the rotor, a first abutment coacting with the ends of the vanes of a portion of the peripheral surface of the rotor, a second abutment coacting with the ends of the vanes of another portion of said surface, one of said abutments being adjustable radially with respect to the surface of the rotor to vary the capacity of the pump or motor, a member extending in a circumferential direction forming a vane track element connecting said abutments to guide the vanes radially as they pass therebetween, said member being secured at one end to one of said abutments, and at its opposite end having a rigid portion, said member having a flexible portion, and means carried by the other of said abutments for maintaining the track surfaces of said rigid portion and of said other abutment

even and for rocking said rigid portion to alter and control the configuration of said flexible portion when the adjustable abutment is moved to change the capacity of the pump or motor, thereby providing the right curvature in said member to produce a smooth guiding of the vanes at all capacities.

11. In a rotary pump or motor of variable capacity, a rotor, a plurality of vanes movable inwardly and outwardly of said rotor, a casing therefor including a first abutment coacting with the ends of the vanes of a portion of the peripheral surface of the rotor, a second abutment coacting with the ends of the vanes of another portion of said surface, one of said abutments being adjustable radially with respect to the surface of the rotor to vary the capacity of the pump or motor, a member extending in a circumferential direction and forming a vane track element connecting said abutments to guide the vanes radially as they pass therebetween, said member being secured at one end to one of said abutments, and at its opposite end having a rigid portion having a track surface, said member having a flexible portion, the other of said abutments having a rigid arm having a track surface and means on said arm coacting with said rigid portion to maintain said track surfaces even and for altering and controlling the configuration of said flexible portion when the adjustable abutment is moved to change the capacity of the pump or motor, thereby providing the right curvature in said member to produce a smooth guiding of the vanes at all capacities.

12. In a rotary pump or motor of variable capacity, a rotor, a plurality of vanes movable inwardly and outwardly of said rotor, a casing therefor including a first abutment coacting with the ends of the vanes of a portion of the peripheral surface of the rotor, a second abutment coacting with the ends of the vanes of another portion of said surface, one of said abutments being adjustable radially with respect to the surface of the rotor to vary the capacity of the pump or motor, and a member extending in a circumferential direction forming a vane track element connecting said abutments to guide the vanes radially as they pass therebetween, said member being secured at one end to one of said abutments, and at its opposite end having a rigid portion having a track surface said member having a flexible portion, the other of said abutments being provided with a pair of spaced rigid arms having track surfaces, said rigid portion being disposed between said arms, a pair of keys carried by said arms, said rigid portion having sliding surfaces coacting with said keys to maintain the track surfaces of said element and said arms in alignment and to alter and control the configuration of said flexible portion conformably to the position to which said adjustable element is adjusted.

13. In a rotary pump or motor of variable capacity, a rotor, a plurality of vanes movable inwardly and outwardly of said rotor, a casing therefor including a first abutment coacting with the ends of the vanes of a portion of the peripheral surface of the rotor, a second abutment coacting with the ends of the vanes of another portion of said surface, one of said abutments being adjustable radially with respect to the surface of the rotor to vary the capacity of the pump or motor, a member extending in a circumferential direction forming a vane track element connecting said abutments to guide the vanes ra-

dially as they pass therebetween, said member being secured at one end to one of said abutments, and at its opposite end having a rigid portion having a track surface, said member having a flexible portion, and means carried by the other of said abutments for maintaining alignment of the track surfaces on said rigid portion and on said other abutment, and means carried by the casing for rocking said rigid portion to alter and control the configuration of said flexible portion conformably to the adjusted position of said adjustable abutment.

14. In a rotary pump or motor of variable capacity, a rotor, a plurality of vanes movable inwardly and outwardly of said rotor, a casing therefor including a first abutment coacting with the ends of the vanes of a portion of the peripheral surface of the rotor, a second abutment coacting with the ends of the vanes of another portion of said surface, one of said abutments being adjustable radially with respect to the surface of the rotor to vary the capacity of the pump or motor, a member extending in a circumferential direction forming a vane track element connecting said abutments to guide the vanes radially as they pass therebetween, said member being secured at one end to one of said abutments, and at its opposite end having a rigid portion having a track surface, a lever projecting from said rigid portion, said member having a flexible portion, means carried by the other of said abutments for maintaining alignment between the track surface of said rigid portion and of said abutment and forming a pivot for said lever, and means on said casing for causing said lever to rock about said pivot and alter and control the configuration of said flexible portion conformably to the adjusted position of said adjustable abutment.

15. In a rotary pump or motor of variable capacity, a rotor, a plurality of vanes movable inwardly and outwardly of said rotor, a casing therefor including a first abutment coacting with the ends of the vanes of a portion of the peripheral surface of the rotor, a second abutment coacting with the ends of the vanes of another portion of said surface, one of said abutments being adjustable radially with respect to the surface of the rotor to vary the capacity of the pump or motor, a member extending in a circumferential direction forming a vane track element connecting said abutments to guide the vanes radially as they pass therebetween, said member being secured at one end to one of said abutments, and at its opposite end having a rigid portion provided with a track surface, said member having a flexible portion, means on the other of said abutments coacting with said rigid portion to maintain alignment between the track surface thereof and the track surface of said abutment and forming a pivot about which said rigid portion may rock, said casing having a slot therein, and a lever fixed to said rigid portion the outer portion of which is adapted to coact with said slot to cause the rocking of said rigid portion so as to alter and control the configuration of said flexible portion conformably to the adjusted position of said adjustable abutment.

16. In a rotary pump or motor of variable capacity, a rotor, a plurality of vanes movable inwardly and outwardly of said rotor, a casing therefor including side walls coacting with the sides of the rotor, a track for said vanes including a rigid element and a flexible element, said

elements having track surfaces adapted to contact with and radially guide said vanes, means for adjusting one of said elements with respect to the other and to the rotor to alter the capacity of said pump or motor and to vary the circumferential length of said track, and means carried by said track elements and actuated simultaneously with said adjusting means for exerting force upon said flexible element to alter and control its shape.

17. In a rotary pump or motor of variable capacity, a rotor, a plurality of vanes movable inwardly and outwardly of said rotor, a casing therefor including a first abutment coacting with the ends of the vanes of a portion of the peripheral surface of the rotor, a second abutment coacting with the ends of the vanes of another portion of said surface, each of said abutments being adjustable radially with respect to the surface of the rotor to vary the capacity of the pump or motor, a member extending in a circumferential direction forming a vane track element connecting said abutments to guide the vanes radially as they pass therebetween, said member being secured at one end to one of said abutments, and at its opposite end having a sliding connection with the other of said abutments, said member having a flexible portion, and means carried by the abutment having said slideable connection for altering and controlling the configuration of said member, and means for radially adjusting either of said abutments while maintaining the other in close proximity to the surface of the rotor to vary the capacity of the pump or motor.

18. In a rotary pump or motor of variable capacity, a rotor, a plurality of vanes movable inwardly and outwardly of said rotor, a casing therefor including a first abutment coacting with the ends of the vanes of a portion of the peripheral surface of the rotor, a second abutment coacting with the ends of the vanes of another portion of said surface, both of said abutments being adjustable radially with respect to the surface of the rotor to vary the capacity of the pump or motor, a member extending in a circumferential direction forming a vane track element connecting said abutments to guide the vanes radially as they pass therebetween, said member being secured at one end to one of said abutments, and at its opposite end having a sliding connection with the other of said abutments, said member having a flexible portion, means carried by the abutment having said slideable connections for altering and controlling the configuration of said member, and means for simultaneously adjusting both of said abutments relative to the surface of the rotor, one abutment being moved outwardly while the other is moved inwardly to vary the capacity of the pump or motor.

19. In a pump or motor of variable capacity, a rotor having a plurality of vanes movable inwardly and outwardly thereof and a vane track

of variable circumferential length surrounding said rotor and said vanes, said vane track including a pair of circumferentially spaced rigid track elements movable with respect to each other whereby the radial distance of the track surface of either of said spaced track elements from the rotor may be made less than, equal to or greater than the radial distance of the track surface of the other of said spaced track elements from said rotor, and said vane track also including a flexible track element intermediate said spaced rigid track elements and adapted to connect therewith to form a substantially continuous track for said vanes in all positions of relative movement between said spaced track elements.

20. In a rotary pump or motor having a rotor, a plurality of vanes movable inwardly and outwardly of said rotor, a casing therefor having an adjustable abutment coacting with the ends of the vanes of one portion of the surface of said rotor, and a fixed abutment coacting with the ends of the vanes of another portion of the surface of said rotor, said casing having a radial aperture provided with an inner shoulder, said fixed abutment comprising a rod-like member adapted to be received in said aperture and having an enlargement at its inner end having a vane track surface thereon and adapted to be held against said inner shoulder, a vane track member having a central portion and flexible end portions, said central portion having an aperture therein and adapted to be received upon said rod-like member and held against said shoulder by said enlarged end portion of the rod-like member.

21. In a rotary pump or motor of variable capacity, a rotor, a plurality of vanes movable inwardly and outwardly of said rotor, a casing therefor including a first abutment coacting with the ends of the vanes of a portion of the peripheral surface of the rotor, a second abutment coacting with the ends of the vanes of another portion of said surface, one of said abutments being adjustable radially with respect to the surface of the rotor to vary the capacity of the pump or motor, a member extending in a circumferential direction and forming a vane track element connecting said abutments to guide the vanes radially as they pass therebetween, said member being secured at one end to one of said abutments, said member having a flexible portion, and means carried by the opposite end of said member and by the said other abutment contiguous to said end for maintaining the track surface of said end substantially even with the corresponding surface of said contiguous abutment and for flexing said member when the adjustable abutment is moved to change the capacity of the pump or motor, thereby providing the right curvature to produce a smooth guiding of the vanes at all capacities.

HUGO A. CENTERVALL.

CERTIFICATE OF CORRECTION.

Patent No. 2,141,171.

December 27, 1938.

HUGO A. CENTERVALL.

It is hereby certified that error appears in the printed specification of the above numbered patent requiring correction as follows: Page 4, first column, line 15, for the word "or" read of; line 60, for "These" read The; page 5, second column, line 22, for "Through" read Throughout; page 7, first column, line 44, for "function" read functioning; and second column, line 69-70, for "conveniently" read conveniently; page 12, first column, line 55, claim 18, for "connections" read connection; and that the said Letters Patent should be read with this correction therein that the same may conform to the record of the case in the Patent Office.

Signed and sealed this 14th day of February, A. D. 1939.

Henry Van Arsdale.
